DRIP CATCHING ATTACHMENTS FOR
UMBRELLAS

Clarence D. De Lamater, San Diego, Calif.

Application July 29, 1940, Serial No. 348,158

3 Claims. (Cl. 135—48)

My invention relates to a drip catching attachment for umbrellas, more particularly adapted and arranged to catch the dripping from umbrellas when folded and in some indoor position and the principal objects of this invention are improvements over my Patent No. 2,170,236 issued August 22, 1939, for Drip catching attachment for umbrellas, and the objects of said improvements are:

First, to provide a device of this class in which the collected mass of drippings does not spill when moving or considerably tilting the umbrella on which said device is positioned;

Second, to provide a device of this class which is readily, easily and quickly applicable to either the ferrules of ladies' or gentlemen's umbrellas;

Third, to provide a device of this class which is very light in weight and which adds a pleasing streamlined appearance to the umbrella on which it is positioned;

Fourth, to provide a device of this class which may be made of various colored materials providing a harmonizing model for use in connection with each individually colored umbrella;

Fifth, to provide a device of this class which is arranged to fit ferrules of substantially all umbrellas now in use and which maintains a firm frictional grip on the ferrule of the umbrella when positioned thereon;

Sixth, to provide a device of this class which is provided with a drip catching reservoir portion ample in size to retain all drippings from the umbrella to which it is attached;

Seventh, to provide a device of this class which is arranged to support umbrellas in upright position when folded by means of a vacuum cup portion of said device; and

Eighth, to provide a device of this class which is very simple and economical of construction, durable, efficient and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a top or plan view of my drip catching attachment for umbrellas; Fig. 2 is a longitudinal sectional view taken from the line 2—2 of Fig. 1 and Fig. 3 is a fragmentary sectional view taken on the same plane as that

shown in Fig. 2, showing by dash lines the ferrule of a man's umbrella positioned and extending through the lower portion of my drip catching attachment for umbrellas.

5 Similar characters of reference refer to similar parts and portions throughout the several views of the drawing.

In the construction of my drip catching attachment for umbrellas I have provided a device which is preferably made of one piece of molded rubber, or other suitable materials, and this device is provided with a centrally positioned ferrule engaging portion 1 which is resilient and is arranged to provide frictional engagement of my 10 drip catching attachment with the umbrella ferrule. The recess 1a in the portion 1 is arranged to receive the ferrule of ladies' umbrellas, which ferrules are of substantially short stubby construction. The bore 1b extending downwardly 15 from the recessed portion 1a is arranged to receive the relatively long narrow ferrule of a man's umbrella, it being noted that the bottom portion of this bore 1b is closed by the portion 1c, as shown best in Fig. 2 of the drawing. The man's 20 umbrella ferrule, as indicated at A in Fig. 3 of the drawing, by dash lines may be forced through the portion 1c so that the ferrule of the man's umbrella extends outwardly, as indicated by dash line A in Fig. 3 of the drawing. Surrounding the 25 portion 1c and extending downwardly therefrom is a vacuum cup portion 1d, which vacuum cup portion 1d is arranged to engage relatively smooth surfaces for holding the umbrella together with my drip catching attachment in upright position 30 so that water on the umbrella may drain downwardly into the reservoir portion 1e surrounding the upwardly extending portion 1, as shown best in Fig. 2 of the drawing. It will be noted that the upwardly extending portion 1 is integral 35 with the vacuum cup portion 1d and that the reservoir portion 1e is formed in integral outwardly diverging relation with the upwardly extending portion 1, as shown best in Fig. 2 of the drawing. The outwardly diverging side portions 40 45 1f form the side walls of the reservoir portion 1e and these side wall portions 1f are arranged in upwardly and inwardly curving form, as shown best in Fig. 2 of the drawing providing an annular reduced curved bead portion 1g which is 50 arranged to surround the umbrella ferrule, as shown by dash line B in Fig. 2 of the drawing.

The operation of my drip catching attachment for umbrellas is substantially as follows:

As hereinbefore described, it is obvious that this drip catching attachment may be positioned

on either a lady's or man's umbrella. When positioned on the ferrule of an umbrella and the umbrella is brought indoors after being in a storm, the wet umbrella is folded and hung up or positioned in a corner or other suitable positions whereby the water from the umbrella is permitted to drain into the reservoir portion $1e$. This reservoir portion $1e$ is of sufficient capacity to retain all of the water drained from any conventional umbrella. This reservoir portion $1e$ retains the water therein until the user of the umbrella desires to use the umbrella again. The water in the reservoir portion $1e$ remaining from previous use of the umbrella does not spill or slop over the edge of my drip catching attachment, but is retained by the annular reduced inwardly curving portion $1g$ until the umbrella is tilted to a considerable degree whereby the water gradually spills out of the reservoir $1e$ reducing to a minimum the chance of spilling the water on the user of the umbrella or on the umbrella itself. The ferrule engaging recess portion $1a$ is resilient and is arranged to maintain a firm grip on the ferrule of ladies' umbrellas, while the bore portion $1b$ is arranged to frictionally engage the ferrule of a man's umbrella providing a tenacious gripping means which holds the drip catching attachment securely on any umbrella to which it is applied. The vacuum cup portion $1d$ is arranged for use in holding a wet umbrella in upright position upon a floor while draining water from the umbrella and drying the same.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a device of the class described, the combination of a hollow reservoir defining portion, a resilient umbrella tip engaging portion concentrically positioned and extending therein, said umbrella tip engaging portion comprising a relatively large umbrella tip engaging portion and a small staff end engaging portion beyond and in concentric relation therewith.
2. In a device of the class described, the combination of a hollow reservoir defining portion, a resilient umbrella tip engaging portion concentrically positioned and extending therein, said umbrella tip engaging portion comprising a relatively large umbrella tip engaging portion and a small staff end engaging portion beyond and in concentric relation therewith, the inner end of said reservoir defining portion provided with an annular inwardly curved portion and a vacuum cup portion integral with said reservoir defining portion positioned at the extending end of said device.
3. In a drip catching attachment for umbrellas, the combination of a centrally positioned umbrella tip engaging portion provided with a recess portion arranged to engage large diameter umbrella ferrules and also provided with a small diameter umbrella tip engaging portion therein arranged to engage small diameter umbrella tips, a hollow reservoir defining portion surrounding said umbrella tip engaging portion, and a vacuum cup portion on said drip catching attachment positioned on the extending end of said drip catching attachment.

CLARENCE D. DE LAMATER.
